UNITED STATES PATENT OFFICE.

HANSON ROBINSON, OF HANOVER, PENNSYLVANIA, ASSIGNOR TO
AMERICAN FOUNDRY & MACHINE COMPANY, OF HANOVER,
PENNSYLVANIA, A CORPORATION OF PENNSYLVANIA.

METAL-PLANING MACHINE.

No. 822,985.

Specification of Letters Patent.

Patented June 12, 1906.

Application filed August 19, 1903. Serial No. 170,094.

To all whom it may concern:

Be it known that I, HANSON ROBINSON, a citizen of the United States, residing at Hanover, in the county of York and State of Pennsylvania, have invented certain new and useful Improvements in Metal-Planing Machines, of which the following is a specification.

This invention pertains to metal-planing machines, and more particularly to that class known to the trade as "open-side" planers. Such machines comprise, in addition to the usual base or bed and sliding work-table traveling thereon, a column or standard located at one side of the bed and work-table and provided with vertical guides or ways, upon which is mounted an L-shaped "beam" or "tool-head support," the depending portion which gives to the beam its L shape being for the purpose of affording a longer guiding and supporting member than would be afforded by the vertical measurement of the beam alone.

The present invention consists in mounting upon the depending or guiding portion of the beam a supplemental beam capable of being swung in a vertical plane through a greater or less number of degrees and in turn carrying a secondary tool-head. It further consists in a novel arrangement of gearing or transmitting devices whereby the secondary tool-head may be adjusted upon and relatively to its beam or support.

The invention is illustrated in the accompanying drawings, in which—

Figure 1 is a front elevation of the column and beam with the supplemental beam and the tool-heads above mentioned, a portion only of the column being shown; Fig. 2, a section through the supplemental beam and guiding portion of the main beam, taken on the line 2 2 of Fig. 1; Fig. 3, a section on the line 3 3 of Fig. 1; Figs. 4 and 5, perspective views of the guiding portion of the main beam and the supplemental beam, the latter detached from the former and turned face outward to better show its construction.

The general type of planer here referred to—that is to say, an open-side planer—is well known, and it has the advantage over a two-column planer in that work may be placed

upon and removed from the table from one side regardless of the position of the table and without interference by any column or support at that side of the machine from 55 which the work is handled. It is, however, desirable to operate simultaneously upon different faces of the body carried by the table, and for this reason a secondary tool-head has been mounted upon the depending or 60 guiding portion of the beam. The range of movement and adjustment of such secondary tool-head has, however, been somewhat restricted, so much so as to limit its utility.

The purpose of the present invention is to 65 increase the range of movement and facilitate the adjustment of the secondary tool-head. With this object in view the support is constructed as follows:

A indicates the usual main base or bed, and 70 B the traveling work-table, which latter is reciprocated by suitable mechanism in a manner common and well understood, and hence unnecessary to be herein described. At one side of the main bed and table is located 75 a column or standard C, which is of solid and substantial construction and suitably stiffened and braced to give it great rigidity, a precaution peculiarly necessary because of the long leverage which the overhanging 80 beam has when carrying a tool at considerable distance from the column or standard and especially when a heavy cut is being made.

One face of the column or standard at a 85 right angle to the direction of travel of the work-table and preferably truly vertical is formed or provided with a guiding-rib a of dovetail form in cross-section, its office being to receive and guide the sustaining portion 90 b of the beam D, which, as shown in Fig. 1, is of L shape. The guides may be of any usual form and will advisably, though not necessarily, be provided with the usual gibbs and take-up screws. This, however, is a mere 95 matter of detail in no manner involved in the present invention, hence unnecessary to be elaborated.

Upon the horizontal portion of the beam D is mounted on suitable guides or ways a 100 tool-head E, designed to traverse the beam from end to end, for which purpose a trav-

2

erse-screw F is provided. The tool-head E is of common form and will in practice be furnished with the usual tool-stock and this in turn with such tool as the nature of the work in hand may require. A rod G, suitably splined or feathered, is journaled in the beam D, parallel with the screw F, to traverse the tool head or stock in a manner common in this class of machines. So, too, the usual screw mechanism is or will be provided for raising and lowering the beam D bodily and holding it at any desired elevation. These and other matters not involved in the present invention are omitted as unnecessary to the present description. The depending portion b of beam D is advisably widened out at or about its mid-height to form a turn-table c, suitably recessed to receive a neck or collar d on a supplemental beam H.

The turn-table is provided with an undercut or dovetailed groove or slot e, concentric with the axis of turn-table c, and designed to receive a segmental supporting and bearing rib f on the rear or inner face of supplemental beam H. As this rib will in practice ordinarily constitute more than a semi-circle, it is preferably made in sections and bolted or screwed fast to the beam H or is at least provided with removable end sections (one or more) to facilitate its introduction into the groove or slot e, it being apparent that with the portion b of the main beam D and the supplemental beam H, made as shown in Figs. 4 and 5, a short segmental rib f, integral with said beam H, could be introduced into the groove e by swinging the beam to proper entering position and thence around to its permanent field of action. The annular rib f gives adequate support and stiffening effect to the supplemental beam, the relatively large radius of the turn-table contributing greatly to this end. The neck or collar d serves, however, as the primary pivotal support for the beam, leaving the rib to give the greater support and stiffening effect necessary to produce the results desired in the operation of the machine.

The upper face of beam H is provided with guiding ribs or ways g, upon which is mounted and guided a secondary tool-head I of usual form and construction and designed, as is head E, to receive a tool-stock, which in turn will carry a suitable tool. The details of the tool-head, tool-stock, and tool clamping and adjusting devices are not here involved, and said parts are therefore intentionally omitted. Any well-known and suitable type of tool stock or holder, tool, and adjusting mechanism may be adopted.

J indicates a traverse-screw journaled at or near its ends in bearings in the supplemental beam H, preferably between the guide-ways g and below the outer face or plane thereof. The purpose of this screw is to effect a movement of the tool-head I lengthwise of the beam H, for which purpose the screw passes through an internally-threaded lug or nut h, formed upon or secured to the rear face of tool-head I, as best seen in Fig. 2, and as is customary in connection with tool-heads and tool-stocks in this class of machinery. Screw J carries at one end a small pinion i, which meshes with a similar pinion j, carried by a shaft K, journaled in bearings in the beam H and lying parallel with the screw J. At its inner end, which is close to the axis of turn-table c, the shaft K is provided with a bevel-pinion k, which meshes with a like pinion l, carried by a horizontal shaft m, having a common axis with the turn-table c, neck or collar d, groove e, and annular rib f. This arrangement, it will be seen, permits the beam H to be swung about the axis of its turn-table and also permits the rotation of screw J through the medium of shafts m K and the intermediate pinions in whatever position the beam may stand.

Shaft m carries at its inner end a second bevel-pinion n, which meshes with a pinion o, carried by a shaft L, journaled in a bearing or support p, formed upon or secured to the depending member b of main beam D, as shown in Figs. 1, 3, and 4. The turn-table c is provided with a channel or recess q to receive the shaft L, and, if deemed desirable, it may also support the same against springing or lateral movement, or, in other words, may form a bearing for said shaft. At its upper or outer end shaft L carries a pinion r, which meshes with a pinion s, carried by a shaft M, journaled in suitable bearings or supports on the depending portion b of beam D. Shaft M is preferably squared at its end to receive a hand-wheel, crank, or other device by which to turn it; but any other suitable means for rotating said shaft may be provided. Said shaft maintains a fixed position relatively to the beam D, and whatever the adjustment of the beams D and H rotation of said shaft M will cause a traverse of the tool-head I lengthwise on the beam H in one or the other direction according to the direction in which said shaft is rotated. Screw F and rod G will likewise be provided with any usual or convenient means for imparting rotation thereto.

Details not herein specifically described may be of usual construction and arrangement, and those that are described may be varied within the limits naturally suggesting themselves to the skilled mechanician, the invention consisting, broadly, in combining with the beam and usual tool-head of an open-side planer a supplemental beam adjustable in a vertical plane about a pivot-axis and carrying a tool-head capable of adjustment longitudinally of said supplemental beam. It will of course be understood that absolutely vertical position of the column or

standard or of the guiding-face thereof is not essential, though in practice it is usual and deemed desirable. Shaft M is supported in a bearing or bracket N, bolted fast to the beam H, as indicated in Figs. 2 and 3, the bearing being shown also in Fig. 5. This bearing is cut away, as illustrated in the last-mentioned figure, to give proper room for the movement of the pinions k and l; but by using larger pinions the cutting away may be dispensed with. The construction shown is, however, deemed preferable, because of the lesser space required for the gearing. The guiding portion b may of course be carried above the beam D, if desired, the important point being that it shall be of sufficient length to give proper guidance and steadyng effect and extend also to a point where it may properly receive and carry the supplemental beam.

It will be noted that by reason of the supplemental beam being mounted upon a turn-table carried by the depending guiding portion of the main overhanging beam I am enabled to carry the side tool-saddle to positions close to the under side of the main beam or remote therefrom and at varying distances from the main post or standard. In other words, it may be set high or low and near either side of the work-table at will, and this without disturbing the adjustment of the main beam or the tool-head and tool thereon. It will also be observed that the supplemental beam is wholly supported upon the one member and held by one device, therein differing from angling tool-head supports or ways carried at one end on the horizontal beam and at the other end on the post or standard. The supplemental beam gives the tool a range of adjustment which the common saddle cannot give. In other words, it gives a wide range of adjustment additional to that afforded by the saddle, which latter is retained.

Having thus described my invention, what I claim is—

1. In an open-side planer, the combination of a work-table; a column or standard at one side thereof; a beam overhanging the work-table, having a depending guiding portion, and supported wholly by the column at one side of the work-table; a supplemental beam mounted upon the depending portion of the main beam and adjustable about a pivot-axis; and a tool-head carried by and adjustable longitudinally of said supplemental beam.
2. In combination with the work-support, column, and overhanging beam of an open-side planer, the latter having a depending guiding portion; a supplemental beam carried by said depending portion of the main beam and arranged to swing in a substantially vertical plane; a tool-head mounted upon said supplemental beam; and mechanism, substantially as described, for trav-

ersing said tool-head lengthwise of the supplemental beam.

3. In an open-side planer, the combination of a work-table; a column or standard at one side thereof; a beam carried by said column or standard, overhanging the table, and provided with a depending guiding portion; a supplemental beam mounted upon the depending portion of the main beam and adapted to be swung to a vertical or a horizontal position or to any intermediate angle; a tool-head carried by the main beam; a tool-head carried by the supplemental beam; a traverse-screw for moving the tool-head lengthwise of the supplemental beam; a shaft mounted in bearings upon the main beam; and intermediate gearing connecting said shaft with the traverse-screw of the supplemental beam, substantially as described, whereby said tool-head may be moved lengthwise of said beam. 85

4. In an open-side planer, the combination of a work-table or support; a column or standard at one side thereof; a beam D overhanging the work-table, supported wholly from said column, and provided with upright portion b; a turn-table bed formed in said upright portion; a supplemental beam H provided with a complementary turn-table section and mounted upon the upright portion b; and a tool-head mounted upon said beam H and movable lengthwise thereof. 95

5. In an open-side planer, the combination with a work-support, column C, and overhanging beam D provided with upright portion b; of a supplemental beam H mounted upon said upright portion b and provided with traverse-screw J; tool-head I mounted upon said beam; and gear for rotating said screw J, comprising pinions i, j, shaft K, pinions k, l, shaft m, pinions n, o, shaft L, pinions r, s, and shaft M. 105

6. In an open-side planer, the combination of a work-table or support; a column or standard at one side thereof; a beam mounted and guided upon the column, overhanging the table, and provided with an upright guiding portion; a supplemental beam mounted and adjustable upon the upright guiding portion of the main beam; a tool-head mounted upon the supplemental beam; a traverse-screw mounted in the beam and serving to move the tool-head lengthwise thereof; a shaft carried in bearings in the main beam; and intermediate connections, substantially such as shown and described, between said shaft and the traverse-screw of the supplemental beam, whereby said screw may be rotated to move the tool-head lengthwise of the beam. 115

7. In an open-side planer, the combination of a work-table or support; a column or standard at one side of the same; a beam mounted and guided upon said standard, overhanging the work-table, and provided with a guiding portion b, having a turn-table 125

4
c provided with an annular groove *e*; a supplemental beam *H* swiveled or pivoted upon said turn-table and provided with an annular rib or tongue *f* to enter the groove *e*, said rib or tongue being provided with a removable section, as and for the purpose set forth.

5 In testimony whereof I have signed my

name to this specification in the presence of two subscribing witnesses.

HANSON ROBINSON.
